UNITED STATES PATENT OFFICE.

WILLIAM M. DUNCAN, OF ALTON, ILLINOIS.

SWEEPING DEVICE.

1,357,693.

Specification of Letters Patent. Patented Nov. 2, 1920.

Application filed January 10, 1919. Serial No. 270,568.

To all whom it may concern:

Be it known that I, WILLIAM M. DUNCAN, a citizen of the United States of America, a resident of Alton, in the county of Madison, State of Illinois, have invented certain new and useful Improvements in Sweeping Devices, of which the following is a full, clear, and exact description, reference being had to the accompanying drawings, forming 10 a part of this specification.

This invention relates to improvements in sweeping devices, and more particularly to a sweeping device comprising a succession of sweeps coöperating with each other to 15 pass the sweepings from one point to another. The new device is adapted for use with a traveling furnace grate from which ashes are discharged at one end of the grate to an ash pit below the grate. When so used 20 the series of sweeps are preferably mounted in the ash pit, and the ashes dropping from one end of the grate are discharged into the path of a sweep at one end of the series. Owing to the manner in which the sweeps 25 are mounted and driven, the ashes are passed from one sweep to another and finally delivered to a part of the ash pit from which they can be conveniently removed.

In the preferred form of the invention, 30 the transferring sweeping device comprises a succession of sweep arms, one of which is adapted to occupy a delivery position over the path of another, and these arms are driven to and from their delivery positions, 35 with the result of passing the ashes from one sweep arm to another. The ashes may be thus swept from the rear to the front of the ash pit.

The new device may be mounted in a relatively shallow ash pit, and this is an advantage in some localities where conditions do not permit the use of a deep pit under the grate.

Figure I is a side elevation, partly in 45 section, illustrating a furnace equipped with a sweeping device constructed in accordance with this invention.

Fig. II is a horizontal section showing the ash pit and the sweeping device mounted 50 therein.

Fig. III is a vertical section, partly in elevation, showing the means for transmitting power to the sweeping device.

Fig. IV is a diagrammatical plan view, 55 on a small scale, showing the oscillatory sweep arms mounted in the ash pit.

To illustrate the invention I have shown a furnace provided with a mechanical stoker comprising an endless chain grate supported by a large, portable frame, said frame including side frame members 1 mounted on wheels 2, and rollers 3 arranged between the side frame members. The endless chain grate comprises endless rows of grate links 4 (Fig. I) connected by means of pivots 5. 60 A power shaft 7, mounted in the side frame members 1, is provided with sprocket wheels 8 for transmitting movement to the chain grate. The grate is mounted on the sprocket wheel 8, and also on a plain idle wheel, or 65 roller, 9 the latter being secured to an idle shaft 10. The fuel passes from a hopper 12 (Fig. I) to the top face of the grate, and the grate links travel in the direction indicated by arrows, the ashes being discharged 70 at the rear end of the grate structure. The ashes are thus delivered to an ash pit 13 formed below the grate structure. 75

I will now describe the sweeping device whereby the ashes are swept from the rear 80 end of the ash pit to the front end. 15 designates horizontal sweep arms mounted in the ash pit and movable over the horizontal floor thereof, said sweep arms being mounted adjacent to each other so that one of the 85 arms may move into the path of another, as indicated by arrows in Figs. II and IV. The sweep arm 15 at the rear end of the series moves under the discharge end of the traveling grate structure, and the several 90 arms 15 may be oscillated with the result of passing the ashes from one arm to another, the object being to sweep the ashes to the front end of the ash pit, or to some other 95 point from which they can be conveniently removed.

Each sweep arm 15 is fixed to a vertical shaft 16 provided with a pinion 17, which meshes with a long reciprocating rack bar 18. It is to be understood, however, that the 100 invention is not limited to this particular means for transmitting power to the sweep arms. In the structure I have shown the rack and pinions are located entirely above the sweep arms. The rack is adapted to reciprocate in stationary guide members 19. The rack is driven very slowly, and the sweep arms 15 oscillate in response to the slow reciprocating movements of the rack. The strokes of the rack may be long enough 105 to turn the sweep arms 15 about one revolution, and it is to be understood that the 110

sweep arms turn in opposite directions in response to the reciprocation of the rack. In Fig. IV I have shown several piles of ashes designated A, B, C, D and E located adjacent to the sweep arms. Each of the arms, excepting the arm adjacent to the pile E, occupies a delivery position over the path of one of the other arms. To reach these positions the sweep arms have moved in a counter-clockwise direction, as indicated by arrows in Fig. IV, and the mechanism is so timed that the movement will be reversed when the sweep arms occupy these positions. Therefore, the arms 15, moving in a clockwise direction, will pass away from the piles of ashes, and as the motion continues each arm will again engage a pile of ashes and move it toward the front of the ash pit. For example, in one revolution the arm 15 at the rear of the ash pit will gather a pile of ashes and deliver it to the point indicated by "A" in Fig. IV, whereupon the movement of said arm will be reversed and it will gather another pile, delivering it near the point A. The ashes are thus swept from the rear of the ash pit to the path of the second arm, and in making one revolution this second arm will move from the pile B and gather up the pile A, so as to transfer the pile A to the position indicated by "B." All of the sweep arms move simultaneously and the piles A, B, C and D are each advanced one step in response to each operation of the sweep arms.

To illustrate a suitable means for reciprocating the long rack bar 18, I have shown a short rack section 21 fixed to said rack bar and meshing with a pinion 22 fixed to an oscillatory shaft 23. A bevel gear 24 fixed to the shaft 23 meshes with bevel gears 25 and 26 loosely mounted on a rotary power shaft 27. A double clutch device 28 (Figs. I and II), splined to the power shaft 27, is adapted to engage clutch teeth on the bevel gears 25 and 26. The clutch device 28 turns with the power shaft 27, and it may be shifted to drive either the wheel 25 or the wheel 26, both of said wheels being loosely mounted on the shaft. The means for shifting the clutch device comprises a longitudinally movable slide bar 29, a shifter fork 30 secured to said bar and fitted to the clutch device, and cam actuated arms 31 and 32 fixed to said bar 29. A rotary gear wheel 33 is provided with oppositely disposed cams 31' and 32', which coöperate with the arms 31 and 32 for the purpose of shifting the clutch device 28. These cams 31' and 32' are in the form of arcuate ribs secured to opposite sides of the gear wheel 33 and provided with inclined ends adapted to engage upturned portions of the arms 31 and 32. When the cam 31' passes from the arm 31, the cam 32' engages the arm 32, thereby shifting the clutch device and, thereafter,

when the cam 32' passes from the arm 32, the clutch is shifted through the medium of cam 31' and arm 31. The clutch device 28 is thus shifted on the rotary power shaft 27, so as to alternately transmit movement to the bevel gears 25 and 26, thereby transmitting an oscillatory movement to the bevel gear 24 and shaft 23. The large gear wheel 33 may be driven through the medium of a pinion 34 fixed to the rotary power shaft 27.

I claim:

1. In a transferring sweeping device of the character described, a succession of sweeps movable about fixed axes and in paths adjacent to each other, and operating means whereby said sweeps are oscillated about said fixed axes to transfer the sweepings from one sweep to another. 80

2. In a transferring sweeping device of the character described, a succession of approximately horizontal sweeps one of which is movable over the path of another, and rotary means whereby said sweeps are turned about vertical axes to transfer the sweepings from one sweep to another. 85

3. In a transferring sweeping device of the character described, a succession of oscillatory sweep arms movable about fixed axes and in paths adjacent to each other, and rotary operating means whereby said sweep arms are turned in opposite directions, more than one half of a revolution to pass the sweepings from one arm to another. 95

4. In a transferring sweeping device of the character described, a succession of approximately horizontal sweep arms mounted over the floor to be swept, one of said arms being movable over the path of another, and rotary operating means whereby said arms are turned in opposite directions, more than one half of a revolution so as to pass the sweepings from one arm to another. 100

5. In a transferring sweeping device of the character described, a succession of approximately horizontal sweep arms mounted over the floor to be swept, said sweep arms being movable about approximately vertical axes and being mounted adjacent to each other so that one arm may occupy a delivery position over the path of another arm, and operating means whereby said sweep arms are moved to and from their delivery positions, thereby passing the sweepings from one arm to another. 110

6. In a transferring sweeping device of the character described, a succession of oscillatory sweep arms mounted over the floor to be swept, said sweep arms being approximately horizontal and their axes being approximately vertical, said sweep arms being mounted adjacent to each other so that one arm may occupy an extreme delivery position at the path of another arm, and operating means whereby said sweep arms are 125 130 135

oscillated to and from their delivery positions, thereby delivering the sweepings from one arm to the path of another arm.

7. In a transferring sweeping device of the character described, a succession of approximately horizontal sweep arms mounted over the floor to be swept, oscillatory shafts to which the respective sweep arms are secured, said sweep arms being mounted adjacent to each other so that one arm may occupy a delivery position in the path of another arm, and operating means whereby said shafts and sweep arms are oscillated to move the sweep arms to and from their delivery positions, thereby passing the sweepings from one sweep arm to another.

8. In a transferring sweeping device of the character described, a succession of oscillatory sweep arms mounted over the floor to be swept, said sweep arms being mounted adjacent to each other so that one arm may occupy an extreme delivery position at the path of another arm, rotary operating means, and an automatic reversing device whereby oscillatory movements are transmitted from said operating means to said sweep arms.

9. In a transferring sweeping device of the character described, a succession of ap-

proximately horizontal sweep arms mounted over the floor to be swept, oscillatory shafts to which the respective sweep arms are secured, said sweep arms being mounted adjacent to each other so that one arm may occupy a delivery position in the path of another arm, rotary operating means, and an automatic reversing device whereby oscillatory movements are transmitted from said rotary operating means to said oscillatory shafts.

10. The combination of a continuous traveling grate from which ashes are discharged at one end of the grate structure, an ash pit below the grate, a succession of approximately horizontal sweep arms mounted in said ash pit and movable over the floor thereof, said sweep arms being mounted adjacent to each other so that one arm may occupy a delivery position over the path of another arm, and operating means whereby said sweep arms are turned, more than one half of a revolution to and from their delivery positions so as to pass the ashes from one arm to another.

In testimony that I claim the foregoing I 55
hereunto affix my signature.

WILLIAM M. DUNCAN
